UNITED STATES PATENT OFFICE.

ALEXANDER MICLAUS, JR., OF WASHINGTON, DISTRICT OF COLUMBIA.

AUTOMATIC GUN.

1,136,695.

Specification of Letters Patent.

Patented Apr. 20, 1915.

Application filed December 2, 1914. Serial No. 875,146.

To all whom it may concern:

Be it known that I, ALEXANDER MICLAUS, Jr., a subject of the King of Rumania, residing at Washington, in the District of Columbia, have invented certain new and useful Improvements in Automatic Guns; and I do hereby declare the following to be a full, clear, and exact description of the invention, such as will enable others skilled in the art to which it appertains to make and use the same.

My invention relates to improvements in guns of that type in which the breech mechanism is automatically unlocked by the pressure of the powder gases on the motor piston, and is then forced backward by the pressure of the powder gases on the empty cartridge case, moving the various movable parts against the action of a return spring to the rear and ejecting the cartridge case; while the parts are restored to the initial position by said return spring.

My invention is more especially intended to apply to guns of that type which may be fired continuously automatically as long as the magazine is kept charged with cartridges, or which may be fired single shot, as desired.

My invention will be understood by reference to the accompanying drawings, in which the same parts are indicated by the same reference symbols throughout the several views:—Figure 1 shows a central vertical section through the rear of the barrel and the breech end of the gun, parts being shown in elevation; Fig. 1^a is a similar section showing the gun barrel and the muzzle end of the gun; Figs. 2, 3, 4, 5 and 6 show sections along the lines 2—2, 3—3, 4—4, 5—5 and 6—6, respectively, of Fig. 1, and looking in the direction of the arrows, the parts being shown on a larger scale than Fig. 1; Fig. 7 shows a section along the line 7—7 of Fig. 1^a, and looking in the direction of the arrows; Fig. 8 shows a section along the line 8—8 of Fig. 1, and looking down, and indicates part of the elevating gear and the tripod mount; Fig. 9 is a similar view to Fig. 1, except as seen from the opposite side and with the breech block withdrawn to the rear, and the cartridges being fed to the breech of the gun; Fig. 10 shows a section along the line 10—10 of Fig. 9, and looking in the direction of the arrows; this figure is intended more especially to illustrate the magazine and the method of feeding the

cartridges to the gun, the parts in this view being shown on twice the scale of those shown in Fig. 9; Fig. 11 shows a section along the line 11—11 of Fig. 9, and looking in the direction of the arrows, the parts being shown on the same scale as in Fig. 10; Fig. 12 shows a section along the line 12—12 of Fig. 10, and looking in the direction of the arrows; Fig. 13 shows a section along the line 13—13 of Fig. 10, the section being taken in a horizontal plane through the axis of the barrel, the parts being shown on the same scale as Figs. 1 and 9; Fig. 14 shows a section along the broken line 14—14 of Fig. 1, and looking down; Fig. 15 is a perspective view of the feed piece for feeding the cartridges from the magazine to the gun; Fig. 16 is a perspective view of the safety lever; Fig. 17 is a plan view showing a collapsible mount adapted for use with the gun of this character; Fig. 17^a is a detail showing a spring locking arrangement adapted for use in a mount of the type shown in Fig. 17; Fig. 18 shows a section along the line 18—18 of Fig. 17; Fig. 19 is a detail showing a sleeve to which the socket pin of the gun mount may be swingingly connected, and which may be used either with the mount shown in Fig. 17, or in any convenient place, as in a boat; and Fig. 20 shows a section along the line 20—20 of Fig. 19, and looking in the direction of the arrows, parts being shown in elevation.

A represents the gun barrel, which is preferably mounted in a suitable water jacket, such as A', supplied with water through an opening closed by the plug a³, see Fig. 1^a; or any suitable barrel easing, not shown, may be substituted for the water jacket, if desired. Suitable sights a and a' are provided.

The breech end of the barrel is preferably squared, as shown in Fig. 11, and is secured to the receiver B and to the supporting block D by bolts b, as shown in Figs. 1, 9, 10, 11 and 13. The rear end of the receiver is closed, and is provided with a suitable hand grip C, while the front end is closed by the breech of the barrel and by the webs D' of the supporting block D, and the heel of the supporting block D is provided with the worm segment D² adapted to engage the worm gear E, by means of which the gun may be elevated or depressed for nice adjustment, as will be hereinafter more fully described.

The barrel is provided near its muzzle with a collar F, which is perforated, as at f, to register with the perforation a^0 in the barrel, and said collar F is provided with a cylindrical chamber f' to receive the head 5 of the motor piston G. This cylindrical chamber f' is provided with an opening f^0 to permit the escape of the powder gases therethrough when the motor piston is forced sufficiently to the rear, and a plug f^2 10 is provided in line with the openings f and a^0 to permit the insertion of a cleaning tool should the same become clogged up with detritus from the powder gases, rust, or the like.

The rear end of the motor piston G is provided with a collar G' which is rigidly attached thereto, and which is connected by screw threads to the actuating rod G², 20 which rod passes through a sleeve H which is journaled in the supporting block D and in the bridge I mounted in the receiver, as shown in Figs. 1 and 9. Between this sleeve H and the collar G', the spring G³ 25 is mounted, which normally tends to restore the motor piston to the initial position.

Near its heel the rod G² is provided with a transversely-elongated slot g into which projects the pin k of the lock K for the breech block, which is in the form of a bell-crank lever pivoted in the receiver, as at k', 30 and having its arm k² adapted to engage a notch m in the bottom of the breech block M, and to hold the breech block in the locked position, as shown in Fig. 1, except when the locking arm k² is released as shown in Fig. 9.

It will be seen that when the gun is fired the powder gases will push back the motor piston a slight distance, releasing the locking lever K from engagement with the breech block and permitting the breech block to be forced to the rear by the pressure of the powder gases acting on the base 40 of the empty cartridge case.

The breech block is forced backward against the action of the return spring L and is restored to the initial position by said spring. This spring is held under 50 compression between the abutment b' of the receiver B and the rear end of the breech block, and is mounted on the hollow stem L', which is fast to the rear end of the breech block, as shown in Fig. 1, in which 55 hollow stem the tail of the firing pin N projects. This firing pin N carries a lug N' which is normally pressed upon by the spring N², tending to force the firing pin forward to fire the cartridge. The firing pin is held in the rearward position by 60 means of the cocking toe o of the hand cocking lever O which is connected to the bell crank lever P, having one arm p pivoted to said cocking toe, and the other arm 65 p' connected to the trigger rod P', which

is connected to the trigger P². This cocking toe o is operative only when the gun is being fired by hand. This hand cocking lever is shown in side elevation in Fig. 1, and in plan in Fig. 14.

For automatic firing, a separate cocking lever O' is provided, shown in side elevation in Fig. 9, and in plan in Fig. 14. This is in the form of a bell crank lever having one arm o' perforated to allow the passage 75 therethrough of the rod G² and the other arm o² adapted to engage in front of the lug N' of the firing pin N. This automatic cocking toe o² is normally held in engaging position by the spring O² on the rod G².

The actuating rod G² is provided with a laterally-projecting lug g² which engages the rear face of the arm o' of the automatic cocking lever O' and tends to throw the cocking toe o² out of engagement when the motor piston nears the forward position under the action of the spring G³.

The trigger is normally returned to the forward position by means of the spring P³ engaging the collar P⁴ on the trigger 90 rod P'. It will be noted that as long as the trigger is drawn to the rear, or to the position shown in Fig. 9, the cocking toe will be held out of engagement with the lug N' and automatic firing will continue. 95 As soon as the trigger is released, the spring P³ will return the cocking toe to the position shown in Fig. 1, and will arrest the forward movement of the firing pin, thus automatically preventing the further firing 100 of the gun until the trigger is drawn to the rear again.

The actuating rod G² is provided with a hole or notch g³ in its heel, in which the pin q is secured, which pin passes through a slot in the side of the receiver and is connected to the handle Q having a knob q'. By drawing this handle Q rearward, the motor piston may be drawn rearward by hand to release the locking lever K.

The breech block is provided with a laterally-projecting handle R, provided with a knob r, the inner end r' of which handle is screwed into the breech block as shown in Fig. 2. By pulling back on the handle P, the breech block may be unlocked, and then by drawing back on the handle R it may be drawn to the rear, to the position shown in Fig. 9, and the piece may be loaded either from the magazine or by hand.

In automatic firing, it will only be necessary to start the firing by drawing back on the handles Q and R as aforesaid. After the gun has begun firing automatically, if the trigger be kept drawn to the rear, and the handles Q and R be released, automatic firing will continue indefinitely, so long as the supply of cartridges is fed to the gun.

The breech block carries an extractor J pivoted thereto, see Fig. 13, and having its 120

claw j normally held in engagement with the rim of the cartridge case by means of the spring j' . On the opposite side of the breech block, and secured in or integral with the receiver, is the ejector J' , having a lug j^2 adapted to engage the rim of the cartridge case opposite to the extractor, and to flip the cartridge case through the opening B^o in the side of the receiver, all as shown in Fig. 13.

It will be seen that the breech block yields under pressure of the gases after the projectile passes the opening a^o , thus reducing the recoil.

Having thus described the automatic and hand firing of the gun, I will proceed to describe the feed mechanism, which is automatically operated by the movement of the breech block.

The rear end of the breech block carries a downwardly-projecting tang S , see Figs. 1-4, which is perforated, as at s , to receive the enlarged portion T of the rod T' , journaled between the rear end of the receiver

and the bridge I , and is rocked by means of the engagement of the pin s' , carried by the tang S , and the cam groove t of the rod T' . As the breech block reciprocates this pin will cause this cam groove to rock the rod

T' , and rotate the pinion T^2 carried by said rod, see Fig. 6. This pinion engages the segmental gear U which is loosely mounted on the sleeve H , see Figs. 1, 6 and 9, and carries the pawl U' operated by the spring

U^2 . This pawl engages the teeth v of the ratchet wheel V , which is fast on the sleeve H , thus the partial rotation of the pinion T^2 under the action of the cam groove and pin s' will turn the ratchet wheel V over

one tooth at a time, and any back lash of the ratchet wheel V will be prevented by the pawl U' . This ratchet wheel V is provided with sprocket teeth v' , as shown in Fig. 10, which engage the links of the

sprocket chain W carrying the pushers W' , between which pushers the cartridges are fed from the magazine, as shown in Fig. 10. Opposite the ratchet wheel V there is an idler sprocket wheel V' over which the

sprocket chain passes, as shown in Fig. 10.

The operation of the magazine will be hereinafter described, but assuming the cartridge to be delivered by the sprocket chain W to the rear of the breech, it will be lifted to the elevating position, as shown in Fig. 9 by the feed piece X , which is pivoted to the receiver by a pin passing through the hole x . For convenience of assembly, the pin k' of the breech locking lever K is also

used as a pivot for the feed piece X . This feed piece is provided with a heel x' which, when the breech block is in the closed or nearly closed position, projects into a slot m^o in the bottom of the breech block and allows the forward end of the feed piece to

drop down out of engagement with the breech block when the latter reaches the closed position; but when the breech block nears the open position this heel x' will engage the cam face m^o at the end of the slot in the breech block and will throw the forward end of the feed piece upward, lifting the cartridge to the position shown in Fig. 9.

The feed piece is provided with a shelf x^2 to support the cartridge, which is slotted, as at x^3 , to permit the passage of the sprocket chain W . At the side of the shelf there are stop lugs x^4 and x^5 to keep the cartridge from rolling off, and the lug x^5 is provided with a cam face x^6 to engage the heel of the breech block when the latter nears the closed position and thus positively force the front end of the feed piece down to the position for receiving another cartridge.

The feed piece is steadied in any convenient way, as by means of the friction brake Y , by having the spring plunger y engaging against the curved braking face b^s of the receiver, as shown in Fig. 9.

Referring now to the construction of the magazine, this consists of a box Z having a series of vertical channels z therein, to which the cartridges are ordinarily supplied in any convenient way, as by hand or otherwise, as shown in Fig. 10. For convenience in feeding, the cartridges are shown placed in a box Z' , separated by a number of partitions, into a series of chambers z similar to those in the magazine and with a removable bottom z' , which may be withdrawn when the box is placed on top of the magazine, as shown in Fig. 10, and allow the cartridges to drop from the box in the chambers of the magazine.

For ordinary firing at normal elevations, the top of the magazine may be left open and the cartridges will feed down by gravity; but where it is desired to fire at high elevations, for instance at air craft, a positive means for feeding the cartridges to the feed mechanism should be supplied, for instance such as shown in Fig. 12, where Z^2 represents a door fitted to the magazine and having a series of springs z^2 , one for each chamber of the magazine, adapted to press on top of the cartridges and to press the same toward the sprocket chain W . This door is hinged at one side, as at z^3 , and at the other side has a spring catch z^4 adapted to automatically engage the hook z^5 , as shown in Fig. 12.

It will be noted from an inspection of Fig. 10 that the cartridges will be fed first from the chamber in the magazine farthest from the barrel, and that these chambers will be emptied *seriatim*, so in feeding the gun by hand it will only be necessary to feed into the farthest chamber of the magazine; while all the other chambers of the magazine may

be kept filled with cartridges. By this arrangement, it will be a simple matter to fire slowly by hand, and then, when ready, to fire rapidly automatically, as desired.

5 In order to control the firing of the piece either automatically, single shot, or to lock it against firing at all, I provide a safety lever 1, shown in detail in Fig. 16 and also shown in Figs. 4, 9 and 13. This safety lever is provided with an inwardly-projecting pin 2 having the head 3 which is rounded on one side at 4, and squared on the opposite side as at 5. This lever is provided with a handle 6, all as shown in Fig. 16. A 10 spring plunger 1^a, see Figs. 4 and 9, is provided to lock the part 1 in its adjusted positions. When this handle 6 is swung forward toward the muzzle of the piece, the rounded end 4 projects into the notch m^4 of the breech block and locks the breech block 15 against movement in either direction and also locks the lever O by engagement with the notch o^8 , and thus locks the piece against firing. When the handle 6 is raised to the 20 vertical position, as shown in Fig. 4, and the parts of the gun are in the position as shown in Fig. 1, the rounded end 4 projects into the notch m^4 of the breech block and locks the breech block against movement in 25 either direction. The gun can then be fired a single shot only, and before a succeeding charge can be fired the handle 6 must be swung to the rear in the direction of the hand grip as shown in dotted lines in Fig. 9; 30 thus causing the safety lever to be moved entirely clear of engagement with the breech block. The breech block is then moved rearward toward the hand grip by the hand lever R to the position shown in Fig. 9, and 35 then returned to the forward position by hand, thus causing the old shell to be ejected and the succeeding cartridge to be fed into the barrel. The handle 6 is then raised to the 40 vertical position, causing the rounded end 4 to again project into the notch m^4 and lock the breech block in position for firing another single shot. When the handle 6 is 45 swung to the rear position, toward the hand grip, as shown in Fig. 9, the safety lever will be entirely clear of engagement with the breech block and the gun can be fired 50 automatically indefinitely.

The gun may be mounted on any suitable mount, such, for instance, as the tripod mount shown in Figs. 1^a and 8, and the mount shown in Figs. 17 and 20. Referring now to the mount shown in Figs. 1^a and 8, the supporting block D is hinged in the yoke 10, mounted on the plate 9, to which the tripod legs 11 are adjustably connected, which legs are preferably hollow and may be set at any desired angle by means of the spring-impressed pins 12 engaging the segmental racks 13, and these pins may be 65 pressed backward, for setting the legs in

the desired position, by means of the hand levers 14; thus these legs may be spread apart or set at the desired angle and locked at said angle. Thus the mount may be readily raised so as to fire the piece over earth 70 works, stumps, or the like, or may be lowered very low so that the gunner may fire the same while lying down and thus keep it and himself as much out of sight as possible.

The supporting block D is provided with 75 a segment D² which engages the worm wheel E on the shaft E' which is turned by the hand wheel E² and the handle E^a. This worm shaft is pivoted at one end, as at e, so as to allow the worm E to be swung away 80 from engagement with the segment D². It is provided at its outer end with a collar e', and is journaled in the yoke 17, which is normally pressed outward by the spring 18, and carries the member 19, which may be 85 clamped in the desired position by the spring plunger 21 which automatically locks the said member in the position either for causing the worm E to engage with the segment D², or to be free therefrom.

The gun may be turned in any convenient way on the mount, and is clamped in the desired position by means of the clamp screw 22. The head of the gun mount is provided with a pivot bolt 30, held in the plate 9 by 95 the collar 30^a, see Fig. 1, which is provided with an annular notch 31, which may be used to mount the piece in a suitable standard, or on a field mount. See for instance Figs. 19 and 20, in which the bolt 30 is 100 mounted in a sleeve 31^a and held in place by a spring catch 32. This sleeve may be mounted in the thwart of a boat, or other convenient place, or may be mounted in the eye 40 of the field mount shown in Fig. 17, 105 in which 41 is a longitudinal bar having one cross piece 42 integral with or rigidly attached thereto, and the other cross piece or link 43 sliding thereon and held in the desired position relative to said bar by a pin 110 44 engaging in perforations in said bar. Two of the link members 45 are hinged to the block 46 carrying the axle 47 for the wheel 48; while the opposite link members 45^a have their heads 49 provided with segmental teeth 50 engaging each other, the 115 whole forming a double collapsible toggle joint to which the wheels 47 and 47^a are attached.

By sliding the link 43 longitudinally on 120 the bar 41, the space between the wheels may be increased or decreased, thus rendering the carriage adaptable for narrow or broad roads, or for giving a wide base, or a narrow base of support for the guns. It will be seen 125 that by bringing the wheels close together the wheel carriage may be conveniently dragged over narrow lanes, through woods, or the like, and may be conveniently transported in boats, taking up very little room. 130

Moreover, by bringing the wheels together and turning the piece on its side, the gun and its mount may be very conveniently hidden in high grass, bushes, or the like.

5 For quick adjustment I provide a spring-actuated locking pin 44^a, as shown in Fig. 17^a, mounted in the bracket 51 carried by the link 43 and normally pressed into engagement by a spring 53 engaging the set 10 collar 54. The pin may be withdrawn by the knob 52, and is snapped into engagement by the spring 53.

It will be noted that I have provided a mount which may be raised or lowered at 15 will, or which may be combined with a field mount, or used in connection with a simple standard, as desired. Moreover, it will be obvious that with the herein described construction the gun is capable of being fired 20 at high elevation, as against air craft.

The gun is very light and may be carried bodily by the soldier, or dragged on wheels, as desired.

It will be noted that I provide a gun 25 which can be very readily assembled, or disassembled and connected to the various kinds of mounts referred to; that it does not require any special tools to operate the same; that it has comparatively few parts 30 likely to get out of order; and that it can be operated by one man, but it is preferably operated by two, one to supply the ammunition and the other to point and fire the gun. The gun may be kept firing indefinitely, or 35 until it gets too hot, by a single loader. It will be evident that it may be quickly mounted for use, and as quickly taken down for transport; moreover, by having the magazine closed by a door the magazine 40 may be kept ready for firing automatically without the necessity of re-charging the magazine. The cartridge boxes will be provided ready for use, and there is no likelihood of the cartridges jamming therein, and 45 no special tools are required to feed same.

It will be obvious that various modifications might be made in the herein described apparatus, and in the construction, combination and arrangement of parts which 50 could be used without departing from the spirit of my invention.

Having thus described my invention what I claim and desire to secure by Letters Patent of the United States is:

55 1. In an automatic gun of the character described, the combination with the barrel and receiver, the barrel being perforated near the muzzle to permit the escape of powder gases, of an actuating rod operated 60 by said escaping powder gases, and a return spring for returning said rod to the initial position, a breech block mounted in said receiver and adapted to be moved rearward by the pressure of the powder gases, a return 65 spring for returning said breech block

to the closed position, and a bell crank locking lever pivoted in said receiver and having one arm adapted to engage said breech block and the other arm engaging said actuating rod, the said locking lever being released from engagement with the breech block by the rearward movement of the said actuating rod and being thrown into locking position when said breech block and said actuating rod are in the forward position, 75 substantially as described.

2. In an automatic gun of the character described, the combination with the barrel and receiver, the barrel being perforated near the muzzle to permit the escape of powder gases, of an actuating rod operated by said escaping powder gases, and a return spring for returning said rod to the initial position, with means for reciprocating said actuating rod by hand, when desired, a 80 breech block mounted in said receiver and adapted to be moved rearward by the pressure of the powder gases, a return spring for returning said breech block to the closed position, and a bell-crank locking lever pivoted in said receiver and having one arm adapted to engage said breech block and the other arm engaging said actuating rod, the said locking lever being released from engagement with the breech block by the rearward movement of the said actuating rod and being thrown into locking position when said breech block and said actuating rod are in the forward position, 85 substantially as described.

3. In an automatic gun of the character described, the combination with the barrel and receiver, the barrel being perforated near the muzzle to permit the escape of powder gases, of an actuating rod operated 90 by said escaping powder gases, and a return spring for returning said rod to the initial position, a breech block mounted in said receiver and adapted to be moved rearward by the pressure of the powder gases, a return spring for returning said breech block to the closed position, and a locking lever operated by the reciprocating movement of said actuating rod and adapted to release said breech block when said rod is 95 moved rearward and to lock the breech block when the breech block and actuating rod are in the forward position, with feed mechanism operated by the reciprocating movement of said breech block for feeding 100 the cartridges *seriatim* to the gun, substantially as described.

4. In an automatic gun of the character described, the combination with the barrel and receiver, the barrel being perforated 105 near the muzzle to permit the escape of powder gases, of an actuating rod operated by said escaping powder gases, and a return spring for returning said rod to the initial position, with means for reciprocating said 110

actuating rod by hand, when desired, a breech block mounted in said receiver and adapted to be moved rearward by the pressure of the powder gases, a return spring for returning said breech block to the closed position, and a locking lever operated by the reciprocating movement of said actuating rod and adapted to release said breech block when said rod is moved rearward and 5 to lock the breech block when the breech block and actuating rod are in the forward position, with feed mechanism operated by the reciprocating movement of said breech block for feeding the cartridge *seriatim* to 10 the gun, substantially as described.

5. In an automatic gun of the character described, the combination with the barrel and receiver, the barrel being perforated near the muzzle to permit the escape of 20 powder gases, of an actuating rod operated by said escaping powder gases, and a return spring for returning said rod to the initial position, a breech block mounted in said receiver and adapted to be moved rearward 25 by the pressure of the powder gases, a return spring for returning said breech block to the closed position, and a bell crank locking lever pivoted in said receiver and having one arm adapted to engage said breech 30 block and the other arm engaging said actuating rod, the said locking lever being released from engagement with the breech block by the rearward movement of the said actuating rod and being thrown into locking 35 position when said breech block and said actuating rod are in the forward position, with feed mechanism operated by the reciprocating movement of said breech block for feeding the cartridge *seriatim* to 40 the gun, substantially as described.

6. In an automatic gun of the character described, the combination with the barrel and receiver, the barrel being perforated near the muzzle to permit the escape of 45 powder gases, of an actuating rod operated by said escaping powder gases, and a return spring for returning said rod to the initial position, with means for reciprocating said actuating rod by hand, when desired, a 50 breech block mounted in said receiver and adapted to be moved rearward by the pressure of the powder gases, a return spring for returning said breech block to the closed position, and a bell-crank locking lever pivoted in said receiver and having one arm adapted to engage said breech block and the other arm engaging said actuating rod, the said locking lever being released from engagement with the breech block by the 55 rearward movement of the said actuating rod and being thrown into locking position when said breech block and said actuating rod are in the forward position, with feed mechanism operated by the reciprocating 60 movement of said breech block for feeding

the cartridges *seriatim* to the gun, substantially as described.

7. In an automatic gun of the character described, the combination with the barrel and receiver, the barrel being perforated 70 near the muzzle to permit the escape of powder gases, of an actuating rod operated by said escaping powder gases, and a return spring for returning said rod to the initial position, a breech block mounted in said receiver and adapted to be moved rearward by the pressure of the powder gases, a return spring for returning said breech block to the closed position, and a locking lever operated by the reciprocating movement of 75 said actuating rod and adapted to release said breech block when said rod is moved rearward and to lock the breech block when the breech block and actuating rod are in the forward position, with feed mechanism 80 operated by the reciprocating movement of said breech block for feeding the cartridges *seriatim* to the gun, said feed mechanism comprising a sprocket wheel and a chain driven thereby adapted to deliver the cartridges to the receiver, a vibrating cam driven by said breech block, and a ratchet and pawl arrangement driven by said cam and imparting a step by step motion to said 85 sprocket wheel, substantially as described. 90

8. In an automatic gun of the character described, the combination with the barrel and receiver, the barrel being perforated near the muzzle to permit the escape of powder gases, of an actuating rod operated 100 by said escaping powder gases, and a return spring for returning said rod to the initial position, with means for reciprocating said actuating rod by hand, when desired, a breech block mounted in said receiver and 105 adapted to be moved rearward by the pressure of the powder gases, a return spring for returning said breech block to the closed position, and a locking lever operated by the reciprocating movement of said actuating rod and adapted to release said breech block when the breech block and actuating rod are in the forward position, with feed mechanism 110 operated by the reciprocating movement of said breech block for feeding the cartridges *seriatim* to the gun, said feed mechanism comprising a sprocket wheel and a chain driven thereby adapted to deliver the cartridges to the receiver, a vibrating cam driven by said breech block, and a 115 ratchet and pawl arrangement driven by said cam and imparting a step by step motion to said sprocket wheel, substantially as described. 120

9. In an automatic gun of the character 125 described, the combination with the barrel and receiver, the barrel being perforated near the muzzle to permit the escape of powder gases, of an actuating rod operated by said escaping powder gases, and a return 130

spring for returning said rod to the initial position, a breech block mounted in said receiver and adapted to be moved rearward by the pressure of the powder gases, a return spring for returning said breech block to the closed position, and a bell crank locking lever pivoted in said receiver and having one arm adapted to engage said breech block and the other arm engaging said actuating rod, the said locking lever being released from engagement with the breech block by the rearward movement of the said actuating rod and being thrown into locking position when said breech block and said actuating rod are in the forward position, with feed mechanism operated by the reciprocating movement of said breech block for feeding the cartridges *seriatim* to the gun, said feed mechanism comprising a sprocket wheel and a chain driven thereby adapted to deliver the cartridges to the receiver, a vibrating cam driven by said breech block, and a ratchet and pawl arrangement driven by said cam and imparting a step by step motion to said sprocket wheel, substantially as described.

10. In an automatic gun of the character described, the combination with the barrel and receiver, the barrel being perforated near the muzzle to permit the escape of powder gases, of an actuating rod operated by said escaping powder gases, and a return spring for returning said rod to the initial position, with means for reciprocating said actuating rod by hand, when desired, a breech block mounted in said receiver and adapted to be moved rearward by the pressure of the powder gases, a return spring for returning said breech block to the closed position, and a bell-crank locking lever pivoted in said receiver and having one arm adapted to engage said breech block and the other arm engaging said actuating rod, the said locking lever being released from engagement with the breech block by the rearward movement of the said actuating rod and being thrown into locking position when said breech block and said actuating rod are in the forward position, with feed mechanism operated by the reciprocating movement of said breech block for feeding the cartridges *seriatim* to the gun, said feed mechanism comprising a sprocket wheel and a chain driven thereby adapted to deliver the cartridges to the receiver, a vibrating cam driven by said breech block, and a ratchet and pawl arrangement driven by said cam and imparting a step by step motion to said sprocket wheel, substantially as described.

11. In an automatic gun of the character described, the combination with the barrel and receiver, the barrel being perforated near the muzzle to permit the escape of powder gases, of an actuating rod operated by

said escaping powder gases, and a return spring for returning said rod to the initial position, a breech block mounted in said receiver and adapted to be moved rearward by the pressure of the powder gases, a return spring for returning said breech block to the closed position, and a locking lever operated by the reciprocating movement of said actuating rod and adapted to release said breech block when said rod is moved rearward and to lock the breech block when the breech block and actuating rod are in the forward position, with feed mechanism operated by the reciprocating movement of said breech block for feeding the cartridges *seriatim* to the gun, said feed mechanism comprising a feed piece pivoted in said receiver, and having a front and a rear arm, the rear arm being adapted to be pressed downward by said breech block as the latter moves backward, thereby raising its front arm and carrying the cartridge to the position for feeding same to the gun, said feed mechanism also comprising a sprocket wheel and a chain driven thereby adapted to deliver the cartridges to the receiver, a vibrating cam driven by said breech block, and a ratchet and pawl arrangement driven by said cam and imparting a step by step motion to said sprocket wheel, substantially as described.

12. In an automatic gun of the character described, the combination with the barrel and receiver, the barrel being perforated near the muzzle to permit the escape of powder gases, of an actuating rod operated by said escaping powder gases, and a return spring for returning said rod to the initial position, with means for reciprocating said actuating rod by hand, when desired, a breech block mounted in said receiver and adapted to be moved rearward by the pressure of the powder gases, a return spring for returning said breech block to the closed position, and a locking lever operated by the reciprocating movement of said actuating rod and adapted to release said breech block when the breech block and actuating rod are in the forward position, with feed mechanism operated by the reciprocating movement of said breech block for feeding the cartridges *seriatim* to the gun, said feed mechanism comprising a feed piece pivoted in said receiver, and having a front and a rear arm, the rear arm being adapted to be pressed downward by said breech block as the latter moves backward, thereby raising its front arm and carrying the cartridge to the position for feeding same to the gun, said feed mechanism also comprising a sprocket wheel and a chain driven thereby adapted to deliver the cartridges to the receiver, a vibrating cam driven by said breech block, and a ratchet and pawl arrangement driven by said cam and imparting a step by step motion to said sprocket wheel, substantially as described.

step motion to said sprocket wheel, substantially as described.

13. In an automatic gun of the character described, the combination with the barrel and receiver, the barrel being perforated near the muzzle to permit the escape of powder gases, of an actuating rod operated by said escaping powder gases, and a return spring for returning said rod to the initial positions, a breech block mounted in said receiver and adapted to be moved rearward by the pressure of the powder gases, a return spring for returning said breech block to the closed position, and a bell crank locking lever pivoted in said receiver and having one arm adapted to engage said breech block and the other arm engaging said actuating rod, the said locking lever being released from engagement with the breech block by the rearward movement of the said actuating rod and being thrown into locking position when said breech block and said actuating rod are in the forward position, with feed mechanism operated by the reciprocating movement of said breech block for feeding the cartridges *seriatim* to the gun, said feed mechanism comprising a feed piece pivoted in said receiver, and having a front and a rear arm, the rear arm being adapted to be pressed downward by said breech block as the latter moves backward, thereby raising its front arm and carrying the cartridge to the position for feeding same to the gun, said feed mechanism also comprising a sprocket wheel and a chain driven thereby adapted to deliver the cartridges to the receiver, a vibrating cam driven by said breech block, and a ratchet and pawl arrangement driven by said cam and imparting a step by step motion to said sprocket wheel, substantially as described.

14. In an automatic gun of the character described, the combination with the barrel and receiver, the barrel being perforated near the muzzle to permit the escape of powder gases, of an actuating rod operated by said escaping powder gases, and a return spring for returning said rod to the initial position, with means for reciprocating said actuating rod by hand, when desired, a breech block mounted in said receiver and adapted to be moved rearward by the pressure of the powder gases, a return spring for returning said breech block to the closed position, and a bell crank locking lever pivoted in said receiver and having one arm adapted to engage said breech block and the other arm engaging said actuating rod, the said locking lever being released from engagement with the breech block by the rearward movement of the said actuating rod and being thrown into locking position when said breech block and said actuating rod are in the forward position, with feed mechanism operated by the reciprocating

movement of said breech block for feeding the cartridges *seriatim* to the gun, said feed mechanism comprising a feed piece pivoted in said receiver, and having a front and a rear arm, the rear arm being adapted to be pressed downward by said breech block as the latter moves backward, thereby raising its front arm and carrying the cartridge to the position for feeding same to the gun, said feed mechanism also comprising a sprocket wheel and a chain driven thereby adapted to deliver the cartridges to the receiver, a vibrating cam driven by said breech block, and a ratchet and pawl arrangement driven by said cam and imparting a step by step motion to said sprocket wheel, substantially as described.

15. In an automatic gun of the character described, the combination with the barrel and receiver, the barrel being perforated near the muzzle to permit the escape of powder gases, of an actuating rod operated by said escaping powder gases, and a return spring for returning said rod to the initial position, a breech block mounted in said receiver and adapted to be moved rearward by the pressure of the powder gases, a return spring for returning said breech block to the closed position, a locking lever operated by the reciprocating movement of said actuating rod and adapted to release said breech block when said rod is moved rearward and to lock the breech block when the breech block and actuating rod are in the forward position, a firing pin and firing pin spring carried by said breech block, means for cocking said firing pin, means operated by hand for releasing said firing pin when desired, and means automatically operated by said actuating rod for releasing said firing pin when the breech block is in the closed and locked position, substantially as described.

16. In an automatic gun of the character described, the combination with the barrel and receiver, the barrel being perforated near the muzzle to permit the escape of powder gases, of an actuating rod operated by said escaping powder gases, and a return spring for returning said rod to the initial position, with means for reciprocating said actuating rod by hand, when desired, a breech block mounted in said receiver and adapted to be moved rearward by the pressure of the powder gases, a return spring for returning said breech block to the closed position, and a locking lever operated by the reciprocating movement of said actuating rod and adapted to release said breech block when said rod is moved rearward and to lock the breech block when the breech block and actuating rod are in the forward position, a firing pin and firing pin spring carried by said breech block, means for cocking said firing pin, means operated by hand for

- releasing said firing pin when desired, and means automatically operated by said actuating rod for releasing said firing pin when the breech block is in the closed and locked position, substantially as described. 5

17. In an automatic gun of the character described, the combination with the barrel and receiver, the barrel being perforated near the muzzle to permit the escape of powder gases, of an actuating rod operated by said escaping powder gases, and a return spring for returning said rod to the initial position, a breech block mounted in said receiver and adapted to be moved rearward by the pressure of the powder gases, a return spring for returning said breech block to the closed position, a bell crank locking lever pivoted in said receiver and having one arm adapted to engage said breech block and the other arm engaging said actuating rod, the said locking lever being released from engagement with the breech block by the rearward movement of the actuating rod and being thrown into locking position when said breech block and said actuating rod are in the forward position, a firing pin and firing pin spring carried by said breech block, means for cocking said firing pin, means operated by hand for releasing said firing pin when desired, and means automatically operated by said actuating rod for releasing said firing pin when the breech block is in the closed and locked position, substantially as described. 10 15 20 25 30 35 40 45 50 55 60 65

18. In an automatic gun of the character described, the combination with the barrel and receiver, the barrel being perforated near the muzzle to permit the escape of powder gases, of an actuating rod operated by said escaping powder gases, and a return spring for returning said rod to the initial position, with means for reciprocating said actuating rod by hand, when desired, a breech block mounted in said receiver and adapted to be moved rearward by the pressure of the powder gases, a return spring for returning said breech block to the closed position, and a bell crank locking lever pivoted in said receiver and having one arm adapted to engage said breech and the other arm engaging said actuating rod, the said locking lever being released from engagement with the breech block by the rearward movement of the said actuating rod and being thrown into locking position when said breech block and said actuating rod are in the forward position, a firing pin and firing pin spring carried by said breech block, means for cocking said firing pin, means operated by hand for releasing said firing pin when desired, and means automatically operated by said actuating rod for releasing said firing pin when the breech block is in the closed and locked position, substantially as described. 110 115 120 125 130

19. In an automatic gun of the character described, the combination with the barrel and receiver, the barrel being perforated near the muzzle to permit the escape of powder gases, of an actuating rod operated by said escaping powder gases, and a return spring for returning said rod to the initial position, a breech block mounted in said receiver and adapted to be moved rearward by the pressure of the powder gases, a return spring for returning said breech block to the closed position, a locking lever operated by the reciprocating movement of said actuating rod and adapted to release said breech block when said rod is moved rearward and to lock the breech block when the breech block and actuating rod are in the forward position, a firing pin and firing pin spring carried by said breech block, means for cocking said firing pin, means operated by hand for releasing said firing pin when desired, and means automatically operated by said actuating rod for releasing said firing pin when the breech block is in the closed and locked position, with a safety lever pivoted to the receiver, and means controlled thereby for either locking the piece against being fired, or for adjusting same for single shot fire or for automatic fire, substantially as described. 70 75 80 85 90 95 100 105 110 115 120 125 130

20. In an automatic gun of the character described, the combination with the barrel and receiver, the barrel being perforated near the muzzle to permit the escape of powder gases, of an actuating rod operated by said escaping powder gases, and a return spring for returning said rod to the initial position, with means for reciprocating said actuating rod by hand, when desired, a breech block mounted in said receiver and adapted to be moved rearward by the pressure of the powder gases, a return spring for returning said breech block to the closed position, and a locking lever operated by the reciprocating movement of said actuating rod and adapted to release said breech block when said rod is moved rearward and to lock the breech block when the breech block and actuating rod are in the forward position, a firing pin and firing pin spring carried by said breech block, means for cocking said firing pin, means operated by hand for releasing said firing pin when desired, and means automatically operated by said actuating rod for releasing said firing pin when the breech block is in the closed and locked position, with a safety lever pivoted to the receiver, and means controlled thereby for either locking the piece against being fired, or for adjusting same for single shot fire or for automatic fire, substantially as described. 100 105 110 115 120 125 130

21. In an automatic gun of the character described, the combination with the barrel and receiver, the barrel being perforated near the muzzle to permit the escape of powder gases, of an actuating rod operated by said escaping powder gases, and a return spring for returning said rod to the initial position, a breech block mounted in said receiver and adapted to be moved rearward by the pressure of the powder gases, a return spring for returning said breech block to the closed position, a locking lever operated by the reciprocating movement of said actuating rod and adapted to release said breech block when said rod is moved rearward and to lock the breech block when the breech block and actuating rod are in the forward position, a firing pin and firing pin spring carried by said breech block, means for cocking said firing pin, means operated by hand for releasing said firing pin when desired, and means automatically operated by said actuating rod for releasing said firing pin when the breech block is in the closed and locked position, with a safety lever pivoted to the receiver, and means controlled thereby for either locking the piece against being fired, or for adjusting same for single shot fire or for automatic fire, substantially as described. 130

der gases, of an actuating rod operated by said escaping powder gases, and a return spring for returning said rod to the initial position, a breech block mounted in said receiver and adapted to be moved rearward by the pressure of the powder gases, a return spring for returning said breech block to the closed position, a bell crank locking lever pivoted in said receiver and having one arm adapted to engage said breech block and the other arm engaging said actuating rod, the said locking lever being released from engagement with the breech block by the rearward movement of the actuating rod and being thrown into locking position when said breech block and said actuating rod are in the forward position, a firing pin and firing pin spring carried by said breech block, means for cocking said firing pin, means operated by hand for releasing said firing pin when desired, and means automatically operated by said actuating rod for releasing said firing pin when the breech block is in the closed and locked position, with a safety lever pivoted to the receiver, and means controlled thereby for either locking the piece against being fired, or for adjusting same for single shot or for automatic fire, substantially as described.

22. In an automatic gun of the character described, the combustion with the barrel and receiver, the barrel being perforated near the muzzle to permit the escape of powder gases, of an actuating rod operated by said escaping powder gases, and a return spring for returning said rod to the initial position, with means for reciprocating said actuating rod by hand, when desired, a breech block mounted in said receiver and adapted to be moved rearward by the pressure of the powder gases, a return spring for returning said breech block to the closed position, and a bell crank locking lever pivoted in said receiver and having one arm adapted to engage said breech block and the other arm engaging said actuating rod, the said locking lever being released from engagement with the breech block by the rearward movement of the said actuating rod and being thrown into locking position when said breech block and said actuating rod are in the forward position, a firing pin and firing pin spring carried by said breech block, means for cocking said firing pin, means operated by hand for releasing said firing pin when desired, and means automatically operated by said actuating rod for releasing said firing pin when the breech block is in the closed and locked position, with a safety lever pivoted to the receiver, and means controlled thereby for either locking the piece against being fired, or for adjusting same for single shot fire, or for automatic fire, substantially as described.

23. In an automatic gun, the combination with a reciprocating breech block of feed mechanism operated thereby comprising a rotary spindle, a cam engagement between said spindle and said breech block whereby said spindle is rocked, a ratchet and pawl arrangement operated by said spindle, a sprocket wheel driven by said ratchet and pawl arrangement, and a sprocket chain adapted to feed the cartridges *seriatim* driven by said sprocket wheel, substantially as described.

24. In an automatic gun, the combination with a reciprocating breech block, of feed mechanism operated thereby comprising a rotary spindle, a cam engagement between said spindle and said breech block whereby said spindle is rocked, a ratchet and pawl arrangement operated by said spindle, a sprocket wheel driven by said ratchet and pawl arrangement, a sprocket chain driven by said sprocket wheel and provided with pusher arms, and means for feeding the cartridges to said sprocket chain between said pusher arms, substantially as described.

25. In an automatic gun, the combination with a reciprocating breech block, of feed mechanism operated thereby comprising a rotary spindle, a cam engagement between said spindle and said breech block whereby said spindle is rocked, a ratchet and pawl arrangement operated by said spindle, a sprocket wheel driven by said ratchet and pawl arrangement, a sprocket chain driven by said sprocket wheel and provided with pusher arms, and a hopper mounted above said sprocket chain and provided with a series of cartridge delivery chambers adapted to feed the cartridges to said sprocket chain between said pusher arms, substantially as described.

26. In an automatic gun, the combination with a reciprocating breech block, of feed mechanism operated thereby comprising a rotary spindle, a cam engagement between said spindle and said breech block whereby said spindle is rocked, a ratchet and pawl arrangement operated by said spindle, a sprocket wheel driven by said ratchet and pawl arrangement, a sprocket chain driven by said sprocket wheel and provided with pusher arms, and a hopper mounted above said sprocket chain and provided with a series of cartridge delivery chambers adapted to feed the cartridges to said sprocket chain between said pusher arms, with means for feeding said cartridges to said hopper, substantially as described.

27. In an automatic gun, the combination with a receiver and a breech block reciprocating therein, of feed mechanism carried by said receiver and actuated by the reciprocating motion of said breech block, comprising a rotary spindle journaled in said receiver, a cam engagement between said spin-

- idle and said breech block for rocking said spindle, a ratchet and pawl arrangement operated by said spindle, a sprocket wheel driven by said ratchet and pawl arrangement, a sprocket chain provided with pusher arms adapted to feed the cartridges *seriatim* to said receiver, and means for feeding the cartridges to said sprocket chain, substantially as described.
28. In an automatic gun, the combination with a receiver and a breech block reciprocating therein, of feed mechanism carried by said receiver and actuated by the reciprocating motion of said breech block, comprising a rotary spindle journaled in said receiver, a cam engagement between said spindle and said breech block for rocking said spindle, a ratchet and pawl arrangement operated by said spindle, a sprocket wheel driven by said ratchet and pawl arrangement, a sprocket chain provided with pusher arms adapted to feed the cartridges *seriatim* to said receiver, with a hopper carried by said receiver and divided into a series of cartridge chambers adapted to deliver the cartridges to said sprocket chain, and means for feeding said cartridges to said hopper, substantially as described.
29. In an automatic gun, the combination with a receiver and a breech block reciprocating therein, of feed mechanism carried by said receiver and actuated by the reciprocating motion of said breech block, comprising a rotary spindle journaled in said receiver, a cam engagement between said spindle and said breech block for rocking said spindle, a ratchet and pawl arrangement operated by said spindle, a sprocket wheel driven by said ratchet and pawl arrangement, a sprocket chain provided with pusher arms adapted to feed the cartridges *seriatim* to said receiver, means for feeding the cartridges to said sprocket chain, and a feed piece pivoted in said receiver and having its rear arm adapted to be pressed downward during the rearward movement of the breech block, and having its forward arm provided with a shelf adapted to lift the cartridges *seriatim* from said sprocket chain into the position to be pushed home by the breech block during its forward movement, with a friction brake carried by said feed piece and engaging a bearing surface on said receiver to steady said feed piece when in operation, substantially as described.
30. In an automatic gun, the combination with a receiver and a breech block reciprocating therein, of feed mechanism carried by said receiver and actuated by the reciprocating motion of said breech block, comprising a rotary spindle journaled in said receiver, a cam engagement between said spindle and said breech block for rocking said spindle, a ratchet and pawl arrangement operated by said spindle, a sprocket wheel driven by said ratchet and pawl arrangement, a sprocket chain provided with pusher arms adapted to feed the cartridges *seriatim* to said receiver, with a hopper carried by said receiver and divided into a series of cartridge chambers adapted to deliver the cartridges to said sprocket chain, means for feeding said cartridges to said hopper, and a feed piece pivoted in said receiver and having its rear arm adapted to be pressed downward during the rearward movement of the breech block, and having its forward arm provided with a shelf adapted to lift the cartridges *seriatim* from said sprocket chain into the position to be pushed home by the breech block during its forward movement, substantially as described.
31. In an automatic gun, the combination with a receiver and a breech block reciprocating therein, of feed mechanism carried by said receiver and actuated by the reciprocating motion of said breech block, comprising a rotary spindle journaled in said receiver, a cam engagement between said spindle and said breech block for rocking said spindle, a ratchet and pawl arrangement operated by said spindle, a sprocket wheel driven by said ratchet and pawl arrangement, a sprocket chain provided with pusher arms adapted to feed the cartridges *seriatim* to said receiver, means for feeding the cartridges to said sprocket chain, and a feed piece pivoted in said receiver and having its rear arm adapted to be pressed downward during the rearward movement of the breech block, and having its forward arm provided with a shelf adapted to lift the cartridges *seriatim* from said sprocket chain into the position to be pushed home by the breech block during its forward movement, with a friction brake carried by said feed piece and engaging a bearing surface on said receiver to steady said feed piece when in operation, substantially as described.
32. In an automatic gun, the combination with a receiver and a breech block reciprocating therein, of feed mechanism carried by said receiver and actuated by the reciprocating motion of said breech block, comprising a rotary spindle journaled in said receiver, a cam engagement between said spindle and said breech block for rocking said spindle, a ratchet and pawl arrangement operated by said spindle, a sprocket wheel driven by said ratchet and pawl arrangement, a sprocket chain provided with pusher arms adapted to feed the cartridges *seriatim* to said receiver, with a hopper carried by said receiver and divided into a series of cartridge chambers adapted to deliver the cartridges to said sprocket chain, means for feeding said cartridges to said hopper, and a feed piece pivoted in said receiver and having its rear arm adapted to be pressed downward during the rearward movement of the breech block, and having its forward arm provided with a shelf

adapted to lift the cartridges *seriatim* from said sprocket chain into the position to be pushed home by the breech block during its forward movement, with a friction brake carried by said feed piece and engaging a bearing surface on said receiver to steady said feed piece when in operation, substantially as described.

33. In an automatic gun, the combination 10 with a receiver and reciprocating breech block mounted therein, of a feed piece pivoted in said receiver and having its rear arm adapted to engage said breech block during its rearward movement, and having 15 its forward arm provided with a shelf adapted to support the cartridge, means for feeding the cartridges *seriatim* to said shelf, and a friction brake carried by said feed piece and engaging said receiver to steady 20 the movement of said feed piece while in operation, substantially as described.

34. In an automatic gun, the combination with a receiver and a breech block reciprocating therein, of feed mechanism carried 25 by said receiver and actuated by the reciprocating motion of said breech block, comprising a rotary spindle journaled in said receiver, a cam engagement between said spindle and said breech block for rocking 30 said spindle, a ratchet and pawl arrangement operated by said spindle, a sprocket wheel driven by said ratchet and pawl arrangement, a sprocket chain provided with pusher arms adapted to feed the cartridges 35 *seriatim* to said receiver, means for feeding the cartridges to said sprocket chain, and a feed piece pivoted in said receiver and having its rear arm adapted to be pressed downward during the rearward movement of the 40 breech block, and having its forward arm provided with a shelf adapted to lift the cartridges *seriatim* from said sprocket chain into the position to be pushed home by the breech block during its forward movement, 45 the forward arm of said feed piece being also provided with a cam face adapted to engage the underside of said breech block and to be pressed down thereby when the breech block moves forward to the closed 50 position, substantially as described.

35. In an automatic gun, the combination with a receiver and a breech block reciprocating therein, of feed mechanism carried 55 by said receiver and actuated by the reciprocating motion of said breech block, comprising a rotary spindle journaled in said receiver, a cam engagement between said spindle and said breech block for rocking 60 said spindle, a ratchet and pawl arrangement operated by said spindle, a sprocket wheel driven by said ratchet and pawl arrangement, a sprocket chain provided with pusher arms adapted to feed the cartridges *seriatim* to said receiver, with a hopper carried by said receiver and divided into a 65

series of cartridge chambers adapted to deliver the cartridges to said sprocket chain, means for feeding said cartridges to said hopper, and a feed piece pivoted in said receiver and having its rear arm adapted to be pressed downward during the rearward movement of the breech block, and having its forward arm provided with a shelf adapted to lift the cartridges *seriatim* from said sprocket chain into the position to be pushed home by the breech block during its forward movement, the forward arm of said feed piece being also provided with a cam face adapted to engage the underside of said breech block and to be pressed down thereby when the breech block moves forward to the closed position, substantially as described.

36. In an automatic gun, the combination with a receiver and a breech block reciprocating therein, of feed mechanism carried by said receiver and actuated by the reciprocating motion of said breech block, comprising a rotary spindle journaled in said receiver, a cam engagement between said spindle and said breech block for rocking said spindle, a ratchet and pawl arrangement operated by said spindle, a sprocket wheel driven by said ratchet and pawl arrangement, a sprocket chain provided with pusher arms adapted to feed the cartridges *seriatim* to said receiver, means for feeding the cartridges to said sprocket chain, and a feed piece pivoted in said receiver and having its rear arm adapted to be pressed downward during the rearward movement of the breech block, and having its forward arm provided with a shelf adapted to lift the cartridges *seriatim* from said sprocket chain into the position to be pushed home by the breech block during its forward movement, with a friction brake carried by said feed piece and engaging a bearing surface on said receiver to steady said feed piece when in operation, the forward arm of said feed piece being also provided with a cam face adapted to engage the underside of said breech block and to be pressed down thereby when the breech block moves forward to the closed position, substantially as described.

37. In an automatic gun, the combination with a receiver and a breech block reciprocating therein, of feed mechanism carried by said receiver and actuated by the reciprocating motion of said breech block, comprising a rotary spindle journaled in said receiver, a cam engagement between said spindle and said breech block for rocking said spindle, a ratchet and pawl arrangement operated by said spindle, a sprocket wheel driven by said ratchet and pawl arrangement, a sprocket chain provided with pusher arms adapted to feed the cartridges *seriatim* to said receiver, with a hopper carried by said receiver and divided into a

series of cartridge chambers adapted to deliver the cartridges to said sprocket chain, means for feeding said cartridges to said hopper, and a feed piece pivoted in said receiver and having its rear arm adapted to be pressed downward during the rearward movement of the breech block, and having its forward arm provided with a shelf adapted to lift the cartridges *seriatim* from said sprocket chain into the position to be pushed home by the breech block during its forward movement, with a friction brake carried by said feed piece and engaging a bearing surface on said receiver to steady said feed piece when in operation, the forward arm of said feed piece being also provided with a cam face adapted to engage the underside of said breech block and to be pressed down thereby when the breech block moves forward to the closed position, substantially as described.

38. In an automatic gun, the combination with a receiver and reciprocating breech block mounted therein, of a feed piece pivoted in said receiver and having its rear arm ²⁵ adapted to engage said breech block during its rearward movement, and having its forward arm provided with a shelf adapted to support the cartridge, with a cam face adapted to be struck by the breech block as ³⁰ it nears the closed position, means for feeding the cartridges *seriatim* to said shelf, and a friction brake carried by said feed piece and engaging said receiver to steady the movement of said feed piece while in operation, substantially as described. ³⁵

In testimony whereof, I affix my signature, in presence of two witnesses.
